CAN OPENER OR SIMILAR ARTICLE

James H. Borland, Smithfield, R. I.

Application August 6, 1951, Serial No. 16,173

Term of patent 14 years

(Cl. D22—2)

To all whom it may concern:

Be it known that I, James H. Borland, a citizen of the United States, residing at Smithfield, State of Rhode Island, have invented a new, original, and ornamental Design for Can Opener or Similar Article, of which the following is a specification, reference being had to the accompanying drawing, forming a part hereof.

In the drawings,

Fig. 1 is a perspective view of a can opener or similar article, showing my novel design; and Fig. 2 is a front view thereof.

I claim:

The ornamental design for a can opener or similar article, as shown.

JAMES H. BORLAND.
